UNITED STATES PATENT OFFICE.

THADDEUS CAHILL, OF NEW YORK, N. Y., ASSIGNOR TO JAMES B. LAMBIE,
E. HILTON JACKSON, GEORGE FREDERICK CAHILL, AND ARTHUR T.
CAHILL, TRUSTEES.

TYPE-WRITING MACHINE OR OTHER KEYBOARD PRINTING INSTRUMENTALITY.

SPECIFICATION forming part of Letters Patent No. 657,479, dated September 4, 1900.

Application filed December 24, 1898. Serial No. 700,234. (No model.)

To all whom it may concern:

Be it known that I, THADDEUS CAHILL, a citizen of the United States, and a resident of the city, county, and State of New York, but temporarily residing at Washington, in the District of Columbia, have invented certain new and useful Improvements in Type-Writing Machines, Type-Setting Machines, or other Keyboard Printing Instrumentalities, of which the following is a specification.

The object of my invention is to make a simple and durable type-writer in which the touch shall be as light as possible, in which the keyboard is readily manipulated by the operator without his looking at all at the keys, so that he is left free to look at his copy uninterruptedly and to write continuously, in which the space at the end of a word shall be conveniently made by depressing the space-key simultaneously with the key which makes the last letter of the word, and in which the operator uses a legato or overlapping touch—that is, depresses one key without having first to release the preceding key; and my invention consists in the parts, improvements, and combinations hereinafter described and claimed.

In some particulars my present invention resembles prior inventions of mine described in United States patents and pending applications; but in other essential features specifically pointed out, and set forth in the statement of claim at the end hereof, it is novel. I make the touch light by using motor mechanism to impel the type-bars and spacing devices, the keys each acting when depressed to connect the proper type-bar with the motor device and to bring said motor device into action for the impelling of said type-bar. Unlike the constructions described in prior United States patents issued to me, I employ a different key for each different type-bar; but I arrange the keyboard in such a manner, shaping the keys to suit the shape of the two hands, that the operator readily manipulates all the keys without ever having to look at any of them. The spacing mechanism and the means by which the operator is enabled to use a legato touch can be best

described in detail hereinafter with reference 50 to the accompanying drawings.

In the accompanying drawings, Figure 1 is a longitudinal vertical section parallel with the length of the keys and transverse to the platen, illustrating certain essential features 55 of my mechanism. Fig. 2 is a sectional view, partly in plan, on the line 2 2, Fig. 1. Fig. 3 is a similar view on the line 3 3, Fig. 1. Figs. 2^a and 3^a illustrate alternative constructions of the mechanism illustrated in Figs. 2 and 60 3. Fig. 4 is a detail rear elevation, partly in section, on the line 4 4, Fig. 1. Fig. 5 is also a detail view, partly in section and partly in elevation, on the line 5 5, Fig. 1. Fig. 6 is a detail rear elevation illustrating the spacing mechanism. Fig. 7 is a detail sectional view, partly in elevation, illustrating certain 65 essential features of the carriage-shifting mechanism. Fig. 8 is a detail view in plan illustrating the same mechanism, certain portions of which are broken away. Fig. 9 is a detail sectional view, partly in elevation, on the line 9 9, Fig. 7. Fig. 10 is a detail view in perspective illustrating one of the parts 70 belonging to the carriage-shifting mechanism, 75 and Fig. 11 is a plan view illustrating the keyboard. Fig. 12 is a view similar to Fig. 1, illustrating certain features of my invention applied to operate the type-releasing devices (or, which is the same thing, the matrix-releasing devices) of a Mergenthaler linotype-machine.

1 is the bed-plate of the main frame, and 2 the top plate.

3 3 3 3 are four posts rising from the bed- 85 plate to support the top plate.

4 4 are posts or standards rising from the bed-plate to support the milled bar 5.

6 6 are similar standards supporting the milled bar 7, and 8 8 are similar standards 90 that serve to support the milled bar 9. Other standards 10 10 and 11 11 serve to support, respectively, the motor-frame 54 and the circuit-closing frame 70.

20 is the platen, 21 the frame of the traveling paper-carriage, and 22 the hinge and guide rod along which the carriage travels and upon which it swings.

23 is the space-rack, and 24 the frame hinged to the traveling paper-carriage and serving to carry the rack 23. The platen-shifting mechanism will be described hereinafter.

5 30 30 are the type-bars, mounted in hangers 31 31, each carrying three types—to wit, (in most cases,) a lower-case letter, the same letter upper-case, and a figure or mark. For convenience the three types are formed upon 10 the same stem.

40 40 are the type-bar-controlling keys, fulcrumed upon pins 41, set in the bar 44.

43 43 are space-keys.

In Fig. 2 thirty keys are shown in the key-board besides the shift-keys. In Fig. 11 twenty-eight keys are shown. Of course a greater or less number of keys may be used, as required. In each case two space-keys 43 43 are used, one on each side of the key-board. The keys, it will be observed, are disposed in two banks—to wit, a bank of long keys, wide in front, and a bank of shorter and narrower keys. They are also disposed, it will be observed, in two groups, 25 one adapted to be operated by the right hand and the other by the left hand, and the arrangement is such that the operator operates them very readily without ever looking at them. They are disposed and shaped to suit 30 the hand. Thus, to refer to Fig. 11, the two keys marked *t* and *m* should be operated normally and regularly by the first or fore finger of the right hand, the two keys marked *s* and *c* by the second finger, the key marked "space-key" and the key marked *v* by the third or ring finger, and the two keys marked *f* and *j* by the little finger. The keys marked *n*, *d*, *g*, and *p* should be operated by the thumb of the right hand, while the keys marked *x* and 35 *q* may be operated either by the thumb or by the forefinger of the right hand—most readily by the forefinger. In like manner the keys marked *o* and *h* should be operated by the forefinger of the left hand, the keys marked *i* and *e* by the second finger of the left hand, the key marked "space-key" and the key marked *a* by the third or ring finger of the left hand, the keys marked *y* and *u* by the little finger of the left hand, the keys marked 40 *r*, *l*, *w*, and *b* by the thumb of the left hand, and the keys marked *k* and *z* by the thumb or forefinger of the left hand—most readily by the forefinger. The keys in the second bank are made of a higher level than the 45 keys of the outer bank. With this arrangement it will be seen that except for four infrequently-occurring letters (the letters "k," "q," "x," and "z," making about one-half of one per cent. of the letters as they occur in a 50 printed page, as illustrated in the drawings, though of course the arrangement of the letters can be altered at will) the fingers and the hands have no lateral displacement whatever and each finger operates two and only two keys always—to wit, the white key to which the finger corresponds and the black key just back of it. The thumb has a lateral move-

ment to select the keys which it controls; but, in fact, the thumb is so hinged that it moves with great dexterity laterally. The 70 whole arrangement is such, as before said, that with very little practice the operator controls all of the letters of the alphabet without ever looking at the keys, without any time being lost in locating them, and with no 75 lateral movement of the fingers or the hands. Also, as it will appear hereinafter, he makes the space at the same time with the last letter of the word by depressing the space-key 80 43 on the same side with the key that makes 85 the last letter of the word. The arrangement of the letters shown in the drawings, Fig. 11, will be found to be an excellent one; but it can of course be varied, if desired. In Fig. 2 it will be seen two additional keys 85 are inserted, which may be used, for example, for the period and comma or for any other characters desired.

50 is a motor-magnet whose core 51 is screwed fast to the milled bar 7. Attached 90 to said core is a brass tube 51^a, within which the armature 52 plays and upon which the energizing-coil is wound. The armature 52 is connected by a rod 52^a with the motor-frame 54, which is supported by centers 55 95 55, set in the standards 10 10.

56 56 are levers corresponding to the type-bars and each connected with the appropriate type-bar by a rod or wire 57. Said levers are fulcrumed upon the rods 58 58, set in the 100 milled bars 5 and 7. To each of the levers 56 is jointed a pendant 59, which is connected by a link 59^a with the arm 60, which is operated by the corresponding key through a releasing-arm 62, bell-crank 61, and pin 61^a. 105 The arms 60 60 and bell-cranks 61 61 are fulcrumed upon the rod 63, which is set in the milled bar 9, and when said bell-cranks occupy their normal positions, with their horizontal arms resting down upon the bar 12, the 110 pendants 59 lie clear of the motor-frame 54; but when any key is depressed by the operator in front of the fulcrum it rises back of the fulcrum and through the releasing arm or latch 62 acting upon the bell-crank 61, 115 arm 60, and link 59^a pulls the pendant 59 (attached to the lever 56, which controls the type-bar corresponding to such key) over the motor-frame 54. At the same time the circuit-closing frame 70, centered by means of 120 points 71, set in the standards 11 11, and which overlies the bell-cranks 61 61, being lifted brings the contact-spring 72, connected with its vertical arm 73, in contact with the adjustable contact-screw 74, thereby closing the 125 circuit of the battery 75 through the magnet 50, which magnet becoming energized attracts its armature, thereby giving movement to the motor-frame 54, and thus (through the pendant 59, controlled by the key depressed, 130 and the lever 56, with which said pendant is connected, and the rod 57) to the appropriate type-bar 30, throwing it up against the printing-point. At the same time the releasing-

frame 80, whose arm 81 is connected by the rod 82 with the arm 54^b of the motor-frame 54, being moved by such motor-frame strikes the releaser-arm 62, which has been lifted by 5 the key depressed, moving said releaser-arm off from the piece 64, attached to the key, thereby disengaging the key and the parts operated thereby and permitting all of said parts to return to their normal positions in 10 advance of the release of the key. To enable the bell-crank 61 to return to its normal position, (thereby to permit the circuit-closing frame 70 to return to its normal position, breaking the circuit of the magnet 50, so that 15 said magnet loses its magnetism,) the bell-crank 61 instead of being connected fast to the link 59^a acts on it through the pin 61^a and arm 60. Thus although the magnet 50 through the motor-frame 54 presses strongly 20 upon the pendant 59 the bell-crank 61 is free to return to its normal position, releasing the frame 70, which, breaking the circuit of the magnet 50, causes its armature 52 and the motor-frame 54 to return to their normal positions, whereupon the lever 56 and type-bar 25 30 return to their normal positions, and the pendant 59, under the influence of the contractile spring 59^b, returns to its normal position.

30 23, as before said, is the space-rack. 90 is the dog-carrying lever, centered at 91. 92 is the fast dog, connected to the dog-carrying lever 90 and to a bridle-lever 93, centered at 94 and carrying a stop 100, adjustable 35 by means of a lock-nut 101. 95 is the loose dog, which is pivoted at 96 to the lever 97, which latter is pivoted at 98 to the dog-carrying lever 90. A flat spring 99 holds the loose dog 95 in its normal position, with its lower wing abutting against the lever 97. In the normal position of the dog-carrying lever 90 the loose dog 95 is in engagement with the rack 23 and is held by the pressure which the usual carriage motor mechanism (not shown in the drawings) 40 exerts upon the carriage and rack 23 (in the direction of the arrow, Fig. 6) with its lower wing engaging the lever 97 and with said lever 97 engaging a screw-stop 100, adjustable 45 in the bridle-lever 93 by means of a lock-nut 101. The motor-frame 54 operates the dog-carrying lever 90 through the push-rod 102, so that when the circuit of the magnet 50 is closed by the depressing of a key the motor-frame receiving movement from said magnet 50 gives movement through the rod 102 to the dog-carrying lever 90, pushes the fast dog 92 up into the pitch of the rack, and then by a continuation of the same motion withdraws 55 the loose dog 95 down out of the rack, whereupon said dog moves (under the influence of the contractile spring 103 upon the lever 97) a tooth-space to the left, as viewed in Fig. 6 from the rear of the machine. When the 60 magnet 50 loses its magnetism and the various parts return to their normal positions, the dog-carrying lever 90 also returns to its

normal position under the influence of the contractile spring 104, and in such movement of return first the loose dog 95 moves 7c up into the pitch of the rack. Then by a continuation of the same movement of the dog-carrying lever the fast dog 92 moves down out of the rack, whereupon the rack and carriage move in the direction of the arrow under the influence of the carriage-motor spring (not shown) a tooth-space, when their further motion is arrested by the lever 97 (to which the loose dog 95 is connected) coming in contact with the adjustable stop 80 100; but if either of the space-keys 43 43 be depressed simultaneously with the key which prints the last letter of a word such key acting through its push-piece 62 upon the frame 110 (which is centered upon the rod 63) rocks 85 said frame in the direction of the arrow, Fig. 1, and thus through the push-rod 111 moves the stop 112 up out of the way of the lever 97, that carries the loose dog 95, so that said loose dog when moved down out of the 90 rack by the action of the motor-magnet 50 now moves under the influence of its contractile spring 103 two tooth-spaces to the left, as viewed from the rear in Fig. 6, so that when the dogs return to their normal 95 positions on the breaking of the circuit of the magnet 50 the carriage now moves two spaces in the direction of the arrow, Fig. 6, until its motion is arrested by the lever 97 coming in contact with the stop 100. 103

Each of the type-bars, as before said, carries three types, and the platen is positioned or "shifted" to enable the different types to print each as required. The three types carried by a type-bar consist of a lower-case 105 letter in the center, an upper-case letter on one side, and a figure or mark on the other side. The platen lies normally in a central position; so that the lower-case letters print, but can be shifted forward or backward to 110 enable the other letters to print. The mechanism for this purpose is as follows:

The frame 21 of the carriage has at the back the brace-rod 120, to which is hinged a yoke-piece 122, which is also hinged to the hinge 115 and guide rod 22 and which has wheels 123 to run thereon, after the fashion fully illustrated in my pending application, Serial No. 673,086, filed March 8, 1898, of which application the application filed October 26, 1899, Serial No. 120 734,864, is a continuation.

Instead of using the shifting mechanism illustrated in the accompanying drawings and hereinbefore described and to which no special importance is attached any other shifting 125 mechanism whatever that is suitable for the purpose may be used.

Instead of using three types on a bar obviously, so far as the other features of my invention are concerned, two types only might 130 be used on each bar or even a single type only on each bar, the number of characters being decreased or the number of keys increased, or both.

At the back of the machine is a rock-shaft 124, supported by lugs extending downward from the top plate of the machine. Said rock-shaft is furnished with arms 125 125, to which the shift-keys 126 126^a (centered at 127) are connected by push-rods 128. Said rock-shaft is also furnished with a vertical arm 129, which is connected by a link 130 with the brace-rod 120. Said link straddles said brace-rod, and the brace-rod slides through said link as the carriage moves. A casting 131, screwed to the top plate of the machine, carries two parallel levers 132 132 (centered at 133) and connected together by a contractile spring 134, which holds both of said levers normally in engagement with opposite sides of the stop 135, attached to the casting 131. These levers serve to hold the carriage normally in its central position (in which the lower-case letters print) and to return it thereto when the shift-keys are released. To this end the link 130 has attached to it or formed upon it a boss or projection 136, lying between the two spring-levers 132 132 and which is held by said levers normally registering with the stop 135, attached to the casting 131. If either of the shift-keys be depressed, said key acting through its push-rod 128 and the corresponding arm 125 of the rock-shaft 124 gives movement to the link 130, brace-rod 120, carriage-frame 21, and platen 20, moving said platen from its normal position until the movement is arrested by one of the spring-pressed levers 132 (upon which the link 130 acts through the part 136) coming against the stop 137, attached to the casting 131. The shift-keys 126 and 126^a, it will be observed, shift the platen in opposite directions from the printing-point. The depressing of one of said keys serves to bring the upper-case type into action, while the depressing of the other of said keys serves to bring the figures and marks into action. Upon the release of the shift-keys the spring 134 returns the parts to their normal positions, in which they are arrested by the spring-pressed levers 132 132 in such positions that the projection 136, formed upon or attached to the link 130, registers with the stop 135, attached to the casting 131. To prevent lateral displacement of the link 130, a guide-bar 138 is attached by screws 139 to the lugs 140 140. My improved action may be applied to other keyboard printing instrumentalities the keys of which correspond to letters or other characters, as well as to a type-writing machine. It may be applied, for example, to linotypes and other type-setting machines. In applying it to such machines it is only necessary to connect the levers 56 56 (which in the accompanying drawings are illustrated as connected to operate the type-bars of a type-writer) with the type-releasing devices or other parts of the linotype or type-setting machine, which serve to make the characters and which the keys of such machine severally operate. Fig. 12 shows my invention applied to operate the escapements or type-releasing

devices of a Mergenthaler linotype-machine. The lever 56 is connected, it will be observed, through the link *h* with the lever *R*, which operates the latches or escapements *r' r'*, that serve to free the matrices *y y*, each as desired, or my improved action may be applied to a type-writing machine (whether of the type-bar or the key-wheel variety) or to a linotype-machine, monotype-machine, type-setting machine, or other keyboard printing instrumentality having keys controlling characters by connecting the levers 56 56 (by the rods 57 57 or in any other suitable manner) to actuate the keys of the instrument to which my improved action may be thus applied. All this is obvious, so that I need not go into the matter further.

The width of the keyboard, as illustrated in the drawings, is somewhat greater, it will be observed, than that of the series of type-bar corresponding levers 56 56. To meet this, in Figs. 2^a and 3^a the links 59^a, that connect the key-operated bell-crank 61 61 with the pendants or movement-receiving arms 59 59, are offset, while in Figs. 2 and 3 the same result is obtained in perhaps a more satisfactory manner by converging the keys toward the back of the machine, so as to bring the series of bell-crank 61 61 into about the same space as the width of the keyboard at the back, thus leaving the links 59^a 59^a to be substantially parallel one with another. These of course are matters of detail which may be varied to almost any extent.

Instead of using an electromagnet as a motor device to operate the pendants 59 and levers 56 and type-bars or other parts connected therewith any other suitable form of motor device might be used—such, for example, as the pneumatic devices commonly used in large organs to operate the valves thereof; but the fact that pneumatics might be substituted for electromagnets in a motor-action for a type-writing machine has been before pointed out by me in the specifications of my previous Letters Patent, No. 600,120, dated March 1, 1898, and No. 604,001, dated May 14, 1898, and of my pending application, Serial No. 522,435, filed September 8, 1894, to all of which reference is hereby had and made, so that it will be unnecessary to say more on the subject here; but it will be understood that whenever in any paragraph of claim at the end hereof a motor or motor device or motor mechanism is mentioned as an element of a combination I use such term "motor" or "motor device" or "motor mechanism" broadly to include any suitable motor, motor device, or motor mechanism, and I do not restrict myself to electric motor mechanism or to an electromagnet as a motor except in those claims in which an electromagnet or electric motor mechanism is expressly and clearly mentioned as an element of the combination, and in so far as certain features of invention residing in my keyboard are concerned such keyboard might be used without any motor

mechanism. Thus, for example, instead of connecting the keys of the keyboard illustrated in the accompanying drawings with the corresponding type-bars by means of a power mechanism said keys might be connected each by a pull-down wire or other usual mechanical connection with the corresponding type-bars, so that the movement communicated by the operator to the key-lever would be employed to actuate the type-bar.

The form of paper-feeding mechanism which I prefer to use, but to which I do not limit myself, consists of (a) means of urging the carriage to the left and (b) spacing mechanism for controlling the movement of the carriage space by space as the printing progresses. In the drawings the usual motor spring or weight for drawing the carriage to the left in the direction of the arrow, Fig. 6, is omitted, being old and well known in the art, and the letter-spacing mechanism illustrated (see particularly Fig. 6) may be modified within wide limits and equivalents substituted for the parts shown without departing from the principles of my invention.

The term "keyboard printing instrumentality" is sometimes used in this specification, particularly in the statement of claim at the end hereof. By the words "keyboard printing instrumentality" I refer to and include not only type-writing machines, but type-setting machines, linotype-machines, and other instrumentalities used in producing type or printing, and in which the successive characters of a line are controlled or selected by putting down the keys of a keyboard.

The term "letter-controlling elements" is sometimes used in this specification, particularly in the statement of claim at the end hereof. By this term "letter-controlling element" I refer to an element which serves by its movement to control the making of a letter.

In some of the paragraphs of claim at the end hereof I speak of an "alphabet of type-bars." By an "alphabet of type-bars" I mean type-bars equal in number to the letters of the alphabet, each carrying a different letter; but by the term "alphabet of type-bars" I do not mean to imply that the complete set of type-bars shall not or may not include other type-bars in addition to the type-bars answering to the letters of the alphabet. In fact, a set of type-bars usually includes, as is well known in the art, type-bars corresponding to the marks and figures as well as type-bars corresponding to the letters, and a single machine may include more than one alphabet of type-bars. In some other paragraphs of claim at the end hereof I speak of an "alphabet of letter-controlling elements," and in such cases I use the word "alphabet" in connection with "letter-controlling elements" in the sense above explained in connection with type-bars—that is, by an alphabet of letter-controlling elements I mean let-

ter-controlling elements equal in number to the letters of the alphabet and each corresponding to and serving to control a different letter of the alphabet.

In several of the paragraphs of claim at the end hereof I speak of a "key-impelled member." By this term "key-impelled member" I mean a member impelled by (that is, receiving motion from) a key.

I do not claim herein anything that is claimed in any of my other pending applications, Serial No. 522,435, filed September 8, 1894, Serial No. 601,520, filed August 3, 1896, Serial No. 684,880, filed June 30, 1898, Serial No. 734,864, filed October 26, 1899, and Serial No. 735,813, filed November 4, 1899. If any one wishes to use any other form of motor mechanism than that shown in the accompanying drawings as a substitute for the mechanism shown, the application above mentioned, Serial No. 522,435, filed September 8, 1894, may be consulted, which shows several radically-different forms of motor mechanism controlled by the keys of a piano to actuate the hammers. From the structure illustrated in the application aforesaid, Serial No. 684,880, filed June 30, 1898, the structure illustrated in the accompanying drawings differs in various particulars, but especially in that the mechanism illustrated in the drawings of the specification filed June 30, 1898, was invented, designed, and constructed with a view to reducing the number of keys, so as to print all the letters of the alphabet by manipulating a few keys readily controlled by one hand, while the mechanism illustrated in the accompanying drawings has been invented, designed, and constructed with a view to employing keys equal in number to the type-bars, so as to make a machine as simple as possible and which may be used by those operators who are wedded to the present mode of striking a different key for each different letter of the alphabet.

The application aforesaid, Serial No. 735,813, filed November 4, 1899, to which reference is hereby had and made, resembles in its structure the structure illustrated in the accompanying drawings in many particulars, but differs in others, as will be readily seen upon a comparison of the two. The three applications, (a) Serial No. 522,435, filed September 8, 1894, (b) Serial No. 684,880, filed June 30, 1898, and (c) the present application, cover distinct but related subject-matter. A different machine is illustrated in the drawings of each of said applications, and the claims of each application are distinct from the claims of the other applications; but there are certain combinations or subcombinations that are common to the three structures illustrated, respectively, in the three applications aforesaid. The application filed September 8, 1894, aforesaid, it will be observed, has not only a number of claims which could only be inserted in that application by reason of the fact that the structural features which they set out as

limitations are found (or some at least of them are found) only in that application; but also said application of September 8, 1894, contains those broad claims which may properly be inserted in some one, and in some one only, of the three applications aforesaid. The claims of the application filed June 30, 1898, Serial No. 684,880, and of this application are narrower than the claims of the application of September 8, 1894, aforesaid, in that many of the claims of said application of September 8, 1894, are broad enough to cover the combinations which said claims set forth, whether such combinations be used in one kind of keyboard instrument or another, (whether they be used, for instance, in a pianoforte or other keyboard musical instrument or in a type-writing machine or other keyboard printing instrumentality,) while each and every of the claims of the application of June 30, 1898, aforesaid, and of this application are limited by some apt form of words to some combination having or including as an essential and indispensable element some part—as, for example, type-bars or letter-controlling mechanism—which is characteristic of and peculiar to a type-writing machine or other keyboard printing instrumentality.

It will be obvious that many modifications may be made in mechanical details without varying from the essential principles of my invention and without material change in result. I do not therefore limit myself to the details hereinbefore shown and described; but

What I do claim in this application as of my own invention, and desire to secure by Letters Patent hereunder, is—

1. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups, one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb, and (c) a plurality of keys in a bank back of the thumb-keys aforesaid and disposed in such a position as to be conveniently operated by the thumb or forefinger.

2. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano

fashion, and consisting of two groups one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb; and (c) a plurality of keys in a bank back of the thumb-keys aforesaid and disposed in such a position as to be conveniently operated by the thumb or forefinger; (C) a paper-carrier; (D) means whereby the same is advanced a step for each letter printed; (E) a space-key in one of the groups aforesaid constructed to be depressed simultaneously with the type-bar-controlling keys; and (F) means controlled by said space-key and acting to make the interverbal space.

3. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) a plurality of keys in each of the two banks aforesaid, normally disposed to be conveniently operated each by the appropriate one of the four fingers, with the hand in its normal position; (b) a plurality of keys arranged to be operated by the thumb, and (c) a plurality of keys in a bank back of the thumb-keys aforesaid and disposed in such a position as to be conveniently operated by the thumb or forefinger; (C) means whereby the paper is advanced as the letters are printed; (D) a space-key in each of the two groups of keys aforesaid, constructed to be depressed simultaneously with the type-bar-controlling keys; and (E) means controlled by said space-keys and acting to cause the production of the interverbal spaces, whereby the interverbal space is made on the part of the operator simultaneously with the last letter of a word, by depressing one of the space-keys aforesaid simultaneously with the type-bar-controlling key corresponding to the final letter of the word.

4. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) a plurality of keys in each of the two banks aforesaid, normally disposed to be con-

- veniently operated each by the appropriate one of the four fingers, with the hand in its normal position; (b) a plurality of keys arranged to be operated by the thumb, and (c) a plurality of keys in a bank back of the thumb-keys aforesaid and disposed in such a position as to be conveniently operated by the thumb or forefinger; (C) means whereby the paper is advanced as the letters are printed; (D) a space-key in one at least of the sets of keys aforesaid, disposed in a position to be operated by the ring-finger when the hand is in its normal position in relation to the keys, and constructed to be operated simultaneously with the type-bar-controlling keys; and (E) means controlled by said space-key and acting to cause the production of the interverbal space, whereby the interverbal space is made on the part of the operator simultaneously with the last letter of a word by depressing the space-key simultaneously with the type-bar-controlling key corresponding to the final letter of the word.
5. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups, one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb; and (c) a plurality of keys in a bank back of the thumb-keys aforesaid and disposed in such a position as to be conveniently operated by the thumb or forefinger; and (C) suitable motor mechanism controlled by the keys aforesaid for impelling the type-bars aforesaid.
6. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb; and (c) a plurality of keys in a bank back of the thumb-keys aforesaid and disposed in such a position as to be conveniently operated by the thumb or forefinger; (C) suitable motor mechanism controlled by the keys aforesaid for impelling the type-bars aforesaid; (D) a paper-carrier; (E) means whereby the same is advanced a step for each letter printed; (F) a space-key in one of the groups aforesaid constructed to be depressed simultaneously with the type-bar-controlling keys; and (G) means controlled by said space-key and acting to make the interverbal space.
7. In a type-writing machine or other similar instrument, and in combination, (A) a multiplicity of type bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) a plurality of keys in each of the two banks aforesaid, normally disposed to be conveniently operated each by the appropriate one of the four fingers, with the hand in its normal position; (b) a plurality of keys arranged to be operated by the thumb, and (c) a plurality of keys in a bank back of the thumb-keys aforesaid and disposed in such a position as to be conveniently operated by the thumb or forefinger; (C) suitable motor mechanism controlled by the keys aforesaid for impelling the type-bars aforesaid; (D) means whereby the paper is advanced as the letters are printed; (E) a space-key in each of the two groups of keys aforesaid, constructed to be depressed simultaneously with the type-bar-controlling keys; and (F) means controlled by said space-keys and acting to cause the production of the interverbal spaces, whereby the interverbal space is made on the part of the operator simultaneously with the last letter of a word by depressing one of the space-keys aforesaid simultaneously with the type-bar-controlling key corresponding to the final letter of the word.
8. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) a plurality of keys in each of the two banks aforesaid, normally disposed to be conveniently operated each by the appropriate one of the four fingers, with the hand in its normal position; (b) a plurality of keys arranged to be operated by the thumb, and (c) a plurality of keys in a bank back of the thumb-keys aforesaid and disposed in such a position as to be conveniently operated by the thumb or forefinger; (C) suitable motor mechanism controlled by the keys aforesaid.

for impelling the type-bars aforesaid; (D) means whereby the paper is advanced as the letters are printed; (E) a space-key in one at least of the sets of keys aforesaid, disposed 5 in a position to be operated by the ring-finger when the hand is in its normal position in relation to the keys, and constructed to be operated simultaneously with the type-bar-controlling keys; and (F) means controlled 10 by said space-key and acting to cause the production of the interverbal spaces, whereby the interverbal space is made on the part of the operator simultaneously with the last letter of a word by depressing the space-key 15 simultaneously with the type-bar-controlling key corresponding to the final letter of the word.

9. In a type-writing machine or other similar instrument, and in combination, (A) a multiplicity of type-bars arranged to strike 20 to a common printing-point, and carrying each three types; (B) shifting mechanism, whereby the different types carried by a bar are caused to print, each as required; (C) 25 keys, equal in number to the type-bars before mentioned, and each connected to control the corresponding type-bar; said keys being arranged in two banks and shaped piano fashion, and consisting of two groups, one 30 for the right hand and the other for the left hand, arranged in juxtaposition, each group including (a) a plurality of keys in each of the two banks aforesaid, normally disposed to be conveniently operated each by the appropriate 35 one of the four fingers, with the hand in its normal position; (b) a plurality of keys arranged to be operated by the thumb; and (c) a plurality of keys in a bank back of the thumb-keys aforesaid and disposed in such a position as to be conveniently operated by the 40 thumb or forefinger; (D) means whereby the paper is advanced as the letters are printed; (E) a space-key in each of the two groups of keys aforesaid, constructed to be depressed simultaneously with the type-bar-controlling 45 keys; and (F) means controlled by said space-keys and acting to cause the production of the interverbal spaces, whereby the interverbal space is made on the part of the operator simultaneously with the last letter of a word, by depressing one of the space-keys aforesaid 50 simultaneously with the type-bar-controlling key corresponding to the final letter of the word.

10. In a type-writing machine or other similar instrument, and in combination, (A) a multiplicity of type-bars arranged to strike 55 to a common printing-point, and carrying each three types; (B) shifting mechanism whereby the different types carried by a bar are caused to print, each as required; (C) keys, equal in number to the type-bars before mentioned, 60 and each connected to control the corresponding type-bar; said keys being arranged in two banks and shaped piano fashion, and consisting of two groups, one for the right hand and the other for the left hand, arranged in juxtaposition, each group including (a) a plurality of keys in each of the two banks aforesaid normally disposed to be conveniently operated each by the appropriate one of the four fingers, with the hand in its 65 normal position; (b) a plurality of keys arranged to be operated by the thumb; (c) a plurality of keys in a bank back of the thumb-keys aforesaid and disposed in such a position as to be conveniently operated by the thumb or forefinger; (D) a paper-carrier; (E) means whereby the same is advanced as the letters are printed; (F) a space-key in one 70

of the groups aforesaid, constructed to be depressed simultaneously with the type-bar-controlling keys; and (G) means controlled 75 by said space-key and acting to make the interverbal space.

11. In a type-writing machine or other similar instrument and in combination, (A) a multiplicity of type-bars arranged to strike 80 to a common printing-point, and carrying each three types; (B) shifting mechanism, whereby the different types carried by a bar are caused to print, each as required; (C) keys, equal in number to the type-bars before mentioned, 85 and each connected to control the corresponding type-bar; said keys being arranged in two banks and shaped piano fashion, and consisting of two groups, one for the right hand and the other for the left hand, arranged in juxtaposition, each group including (a) a plurality of keys in each of the two banks aforesaid, normally disposed to be conveniently operated each by the appropriate one of the four fingers, with the hand in its 90 normal position; (b) a plurality of keys arranged to be operated by the thumb; (c) a plurality of keys in a bank back of the thumb-keys aforesaid and disposed in such a position as to be conveniently operated by the 95 thumb or forefinger; (D) means whereby the paper is advanced as the letters are printed; (E) a space-key in each of the two groups of keys aforesaid, constructed to be depressed simultaneously with the type-bar-controlling 100 keys; and (F) means controlled by said space-keys and acting to cause the production of the interverbal spaces, whereby the interverbal space is made on the part of the operator simultaneously with the last letter of a word, by depressing one of the space-keys aforesaid 105 simultaneously with the type-bar-controlling key corresponding to the final letter of the word.

12. In a type-writing machine or other similar instrument, and in combination, (A) a multiplicity of type-bars arranged to strike 110 to a common printing-point, and carrying each three types; (B) shifting mechanism whereby the different types carried by a bar are caused to print, each as required; (C) keys, equal in number to the type-bars before mentioned, 115 and each connected to control the corresponding type-bar; said keys being arranged in two banks and shaped piano fashion, and consisting of two groups, one for the right hand and the other for the left hand, arranged in juxtaposition, each group including (a) a plurality of keys in each of the two banks aforesaid normally disposed to be conveniently operated each by the appropriate one of the four fingers, with the hand in its 120 normal position; (b) a plurality of keys arranged to be operated by the thumb; (c) a plurality of keys in a bank back of the thumb-keys aforesaid and disposed in such a position as to be conveniently operated by the thumb or forefinger; (D) a space-key in one at 125 least of the groups of keys aforesaid disposed 130

in a position to be operated by the ring-finger when the hand is in its normal position in relation to the keys, and constructed to be operated simultaneously with the type-bar-controlling keys; and (E) means controlled by said space-key and acting to cause the production of the interverbal spaces, whereby the interverbal space is made on the part of the operator simultaneously with the last letter of a word by depressing the space-key simultaneously with the type-bar-controlling key corresponding to the final letter of the word.

13. In combination in a type-writing machine, (a) a plurality of type-bars arranged so that they strike to a common printing-center; (b) a motor device, acting to impel said type-bars, each as required; (c) keys, equal in number to the type-bars impelled by the motor device aforesaid, a key for each type-bar, said keys each acting, when depressed, to connect the corresponding type-bar with the motor device aforesaid to receive movement therefrom; (d) a motor-controlling device operated by one or more of the keys aforesaid, and acting when a key is depressed to bring the motor aforesaid into operation for the impelling of the type-bar connected with it; and (e) means acting to release said motor-controlling device in advance of the release of the key depressed, all the parts being constructed, arranged and operating in such a manner that a succeeding key may be depressed to print while the key first depressed is still held down.

14. In combination in a type-writing machine, (a) a plurality of type-bars arranged so that they strike to a common printing-center; (b) a motor device, acting to impel said type-bars, each as required; (c) keys, equal in number to the type-bars impelled by the motor device aforesaid, a key for each type-bar, said keys each acting, when depressed, to connect the corresponding type-bar with the motor device aforesaid to receive movement therefrom; (d) a motor-controlling device operated by one or more of the keys aforesaid, and acting when a key is depressed to bring the motor aforesaid into operation for the impelling of the type-bar connected with it; and (e) means actuated by the motor device aforesaid, serving when a key is depressed to release the motor-controlling device aforesaid in advance of the release of the key depressed controlling it, all the parts being constructed, arranged and operating in such a manner that a succeeding key may be depressed to print while the key first depressed is still held down.

15. In combination in a type-writing machine or other similar instrument, (a) a plurality of type-bars arranged so that they strike to a common printing-center; (b) an electromagnet acting to impel said type-bars, each as required; (c) keys, equal in number to the type-bars impelled by the electromagnet

aforesaid, a key for each type-bar; said keys each acting when depressed to connect the corresponding type-bar with the electromagnet aforesaid to receive movement therefrom; (d) a circuit-controlling device operated by one or more of the keys aforesaid, and serving when such key is depressed to bring the magnet aforesaid into action to impel the type-bar corresponding to the key depressed; and (e) means acting to permit said circuit-controlling device to return toward its normal position in advance of the release of the key depressed; all the parts being constructed, arranged and operating in such a manner that a succeeding key may be depressed to print while the key first depressed is still held down.

16. In combination in a type-writing machine or other similar instrument, (a) a plurality of type-bars arranged so that they strike to a common printing-center; (b) an electromagnet acting to impel said type-bars, each as required; (c) keys, equal in number to the type-bars impelled by the electromagnet aforesaid, a key for each type-bar; said keys each acting when depressed to connect the corresponding type-bar with the electromagnet aforesaid, to receive movement therefrom; (d) a circuit-controlling device operated by one or more of the keys aforesaid and serving when such key is depressed to bring the magnet aforesaid into action to impel the type-bar corresponding to the key depressed; and (e) means operated by the electromagnet aforesaid, acting when a key is depressed to permit the circuit-controlling device aforesaid to return toward its normal position in advance of the release of said key, all the parts being constructed, arranged and operating in such a manner that a succeeding key may be depressed to print while the key first depressed is still held down.

17. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb; (c) a plurality of keys in a bank back of the thumb-keys aforesaid and disposed in such a position as to be conveniently operated by the thumb or forefinger; (C) a type-bar-impelling motor, the type-bar aforesaid being normally disconnected from said motor; (D) means controlled by the keys aforesaid, acting to connect the

type-bars aforesaid, each as required, with the motor aforesaid, to receive movement therefrom.

18. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb, (c) a plurality of keys in a bank back of the thumb-keys aforesaid and disposed in such a position as to be conveniently operated by the thumb or forefinger; (C) a type-bar-impelling motor, the type-bars aforesaid being normally disconnected from said motor; (D) means controlled by the keys aforesaid, acting to connect the type-bars aforesaid, each as required, with the motor aforesaid, to receive movement therefrom; (E) a paper-carrier; (F) means whereby the same is advanced a step for each letter printed; (G) a space-key in one of the groups aforesaid, constructed to be depressed simultaneously with the type-bar-controlling keys; and (H) means controlled by said space-key and acting to make the interverbal space.

19. In a type-writing machine or other similar instrument, and in combination, (A) a multiplicity of type-bars arranged to strike to a common printing-point; (B) keys, equal in number to the type-bars before mentioned, and each connected to control the corresponding type-bar; the keys of the machine being arranged in two banks and shaped piano fashion, and consisting of two groups, one for the right hand and the other for the left hand, arranged in juxtaposition, each group including (a) a plurality of keys in each of the two banks aforesaid, normally disposed to be conveniently operated each by the appropriate one of the four fingers, with the hand in its normal position; (b) a plurality of keys arranged to be operated by the thumb; (c) a plurality of keys in a bank back of the thumb-keys aforesaid and disposed in such a position as to be conveniently operated by the thumb or forefinger; (C) a type-bar-impelling motor, the type-bars aforesaid being normally disconnected from said motor; (D) means controlled by the keys aforesaid, acting to connect the type-bars aforesaid, each as required, with the motor aforesaid, to receive movement therefrom; (E) means whereby the paper is advanced as the letters are printed; (F) a space-key in each of the sets of keys aforesaid, constructed to be depressed simul-

taneously with the type-bar-controlling keys; and (G) means controlled by said space-keys and acting to cause the production of the interverbal spaces, whereby the interverbal space is made on the part of the operator simultaneously with the last letter of a word by depressing one of the space-keys aforesaid simultaneously with the type-bar-controlling key corresponding to the final letter of the word.

20. In a type-writing machine or other similar instrument, and in combination, (a) a plurality of type-bars; (b) a motor for impelling said type-bars; (c) keys corresponding to the type-bars actuated by the motor aforesaid, a different key for each different type-bar; (d) members equal in number to the type-bars aforesaid, said members being connected each to the corresponding type-bar and serving to receive movement from the motor aforesaid, for the impelling of such type-bar; (e) a connection between each key and the member before mentioned as connected with the type-bar corresponding to such key, wherethrough said key, when depressed, throws said member into operative relation with the motor aforesaid to receive movement therefrom; and (f) means acting upon the connection between the key depressed and the type-bar-connected member corresponding to such key, to disconnect said member from said key, thereby to permit said member to return toward its normal position in advance of the release of said key; all the parts being constructed, arranged and operating in such a manner that when a key is depressed to print a succeeding key may be depressed to print while the key first depressed is still held down.

21. In a type-writing machine or other similar instrument, and in combination, (a) a plurality of type-bars; (b) a type-bar-impelling frame, acting to communicate movement to all the type-bars aforesaid, each as required; (c) keys corresponding to the type-bars actuated by the frame aforesaid, a different key for each different type-bar; (d) members equal in number to the type-bars aforesaid, said members being connected each to the corresponding type-bar and serving to receive movement from the frame aforesaid for the impelling of such type-bar; (e) key-impelled members corresponding to the keys aforesaid, a key-impelled member for each key, each of said key-impelled members acting when its key is depressed to throw the type-bar-connected member aforesaid into operative relation with the frame aforesaid, to receive movement therefrom; and (f) means acting when a key is depressed, to disconnect the key-impelled member aforesaid, corresponding to the key depressed, from said key, thereby to permit said member to return toward its normal position in advance of the release of said key; all the parts being constructed, arranged and operating in such a manner

that when a key is depressed to print a succeeding key may be depressed to print while the key first depressed is still held down.

22. In a type-writing machine or other similar instrument, and in combination, (a) a plurality of type-bars; (b) a type-bar-impelling frame, acting to communicate movement to all the type-bars aforesaid, each as required; (c) keys corresponding to the type-bars actuated by the motor aforesaid, a different key for each different type-bar; (d) members equal in number to the type-bars aforesaid, said members being connected each to the corresponding type-bar and serving to receive movement from the frame aforesaid for the impelling of such type-bar; (e) key-impelled members corresponding to the keys aforesaid, a key-impelled member for each key, each of said key-impelled members acting when its key is depressed to throw the type-bar-connected member aforesaid into operative relation with the frame aforesaid, to receive movement therefrom; the type-bar-impelling frame aforesaid acting also to disconnect the key-impelled member controlled by the key depressed, from such key, thereby to permit said member to return toward its normal position in advance of the release of said key; all the parts being constructed, arranged and operating in such a manner that when a key is depressed to print a succeeding key may be depressed to print while the key first depressed is still held down.

23. In a type-writing machine or other similar instrument, and in combination, (a) a plurality of type-bars; (b) a type-bar-impelling frame, acting to communicate movement to all the type-bars aforesaid, each as required; (c) keys corresponding to the type-bars actuated by the frame aforesaid, a different key for each different type-bar; (d) members equal in number to the type-bars aforesaid, said members being connected each to the corresponding type-bar and serving to receive movement from the frame aforesaid; (e) key-impelled members corresponding to the keys aforesaid, a key-impelled member for each key, each of said key-impelled members acting when its key is depressed to throw the type-bar-connected member aforesaid into operative relation with the frame aforesaid, to receive movement therefrom; and (f) a releasing-frame, connected with the type-bar-impelling frame aforesaid and acting to disconnect the key-impelled member corresponding to the key depressed, from such key, thereby to permit said member to return toward its normal position in advance of the release of said key; all the parts being constructed, arranged and operating in such a manner that when a key is depressed to print a succeeding key may be depressed to print while the key first depressed is still held down.

24. In a type-writing machine or other similar instrument, and in combination, (a) a plurality of type-bars; (b) a motor for actuating said type-bars; (c) keys corresponding to the

type-bars actuated by the motor aforesaid, a different key for each different type-bar; (d) members equal in number to the type-bars aforesaid, said members being connected each to the corresponding type-bar and serving to receive movement from the motor aforesaid for the impelling of such type-bar; (e) key-impelled members corresponding to the keys aforesaid, a key-impelled member for each key, each of said key-impelled members acting when its key is depressed, to throw the type-bar-connected member aforesaid, corresponding to such key, into operative relation with the motor aforesaid, to receive movement therefrom; and (f) means acting to disconnect the key-impelled member aforesaid controlled by the key depressed, from said key, thereby to permit said member to return toward its normal position in advance of the release of said key; all the parts being constructed, arranged and operating in such a manner that when a key is depressed to print a succeeding key may be depressed to print while the key first depressed is still held down.

25. In a type-writing machine or other similar instrument, and in combination, (a) a plurality of type-bars; (b) a motor for actuating said type-bars; (c) keys corresponding to the type-bars actuated by the motor aforesaid, a different key for each different type-bar; (d) members equal in number to the type-bars aforesaid, said members being connected each to the corresponding type-bar and serving to receive movement from the motor aforesaid for the impelling of such type-bar; (e) key-impelled members corresponding to the keys aforesaid, a key-impelled member for each key, each of said key-impelled members acting when its key is depressed to throw the type-bar-connected member aforesaid, corresponding to such key, into operative relation with the motor aforesaid, to receive movement therefrom; the type-bar-impelling motor aforesaid acting also to disconnect the key-impelled member aforesaid, controlled by the key depressed, from said key, thereby to permit said member to return toward its normal position in advance of the release of said key; all the parts being constructed, arranged and operating in such a manner that when a key is depressed to print a succeeding key may be depressed to print while the key first depressed is still held down.

26. In a type-writing machine or other similar instrument, and in combination, (a) a plurality of type-bars; (b) a motor for actuating said type-bars; (c) keys corresponding to the type-bars actuated by the motor aforesaid, a different key for each different type-bar; (d) members equal in number to the type-bars aforesaid, said members being connected each to the corresponding type-bar and serving to receive movement from the motor aforesaid for the impelling of such type-bar; (e) key-impelled members corresponding to the keys aforesaid, a key-impelled member for each

key, each of said key-impelled members acting when its key is depressed, to throw the type-bar-connected member aforesaid, corresponding to said keys into operative relation 5 with the motor aforesaid, to receive movement therefrom; and (f) a frame, actuated by the type-bar-impelling motor aforesaid and acting to disconnect the key-impelled member aforesaid, controlled by the key depressed, from such key, thereby to permit said member to return toward its normal position in advance of the release of said key; all the parts being constructed, arranged and operating in such a manner that when a key 15 is depressed to print a succeeding key may be depressed to print while the key first depressed is still held down.

27. In a type-writing machine or other similar instrument and in combination, (a) a plurality of type-bars; (b) a motor for actuating said type-bars; (c) keys corresponding to the type-bars actuated by the motor aforesaid, a different key for each different type-bar; (d) members equal in number to the type-bars 25 aforesaid, said members being connected each with the corresponding type-bar and serving to receive movement from the motor aforesaid, for the impelling of such type-bar; (e) key-impelled members, corresponding to the 30 keys aforesaid, a key-impelled member for each key, each of said key-impelled members acting when its key is depressed to throw the type-bar-connected member aforesaid into operative relation with the motor aforesaid to receive movement therefrom; (f) motor-controlling means, actuated by the keys through the key-impelled members aforesaid, and acting when the keys are depressed, to bring the motor aforesaid into action for the 35 impelling of the type-bar; and (g) means acting when a key is depressed, to disconnect the key-impelled member corresponding to the key depressed, from such key; thereby to permit said member to return toward its normal position in advance of the release of said key; all the parts being constructed, arranged and operating in such a manner that when a key 45 is depressed to print, a succeeding key may be depressed to print while the key first depressed is still held down.

28. In a type-writing machine or other similar instrument, and in combination, (a) a plurality of type-bars; (b) a motor for actuating said type-bars; (c) keys corresponding to the 55 type-bars actuated by the motor aforesaid, a different key for each different type-bar; (d) members equal in number to the type-bars aforesaid, said members being connected each with the corresponding type-bar and serving 60 to receive movement from the motor aforesaid, for the impelling of such type-bar; (e) key-impelled members corresponding to the keys aforesaid, each of said key-impelled members acting when its key is depressed to throw the type-bar-connected member aforesaid into operative relation with the motor aforesaid to receive movement therefrom;

(f) motor-controlling means actuated by the keys through the key-impelled members aforesaid, and acting when the keys are depressed, to bring the motor aforesaid into action for the impelling of the type-bar; and (g) means acting when a key is depressed, to disconnect the key-impelled member corresponding to the key depressed from such key, thereby to permit said member, and the motor-controlling means actuated by the key, through said member, to return toward their normal positions; the motor-controlling means aforesaid acting by such movement of 80 return to affect the motor device aforesaid so that the same releases the type-bar, corresponding to the key depressed, leaving it free to return toward its normal position in advance of the release of the key; all the parts 85 being constructed, arranged and operating in such a manner that when a key is depressed to print, a succeeding key may be depressed to print while the key first depressed is still held down.

29. In a type-writing machine or other similar instrument, and in combination, (a) a plurality of type-bars; (b) a motor for actuating said type-bars; (c) keys corresponding to the type-bars actuated by the motor aforesaid, a different key for each different type-bar; (d) members equal in number to the type-bars aforesaid, said members being connected each with the corresponding type-bar and serving to receive movement from the motor aforesaid, for the impelling of such type-bar; (e) key-impelled members corresponding to the keys aforesaid, each of said key-impelled members acting when its key is depressed to throw the type-bar-connected member aforesaid into operative relation with the motor aforesaid to receive movement therefrom; (f) a motor-controlling device, actuated by the keys through the key-impelled members aforesaid, and acting when a key is depressed to bring the motor aforesaid into action for the impelling of the type-bar corresponding to such key; the type-bar-impelling motor aforesaid acting to disconnect the key-impelled member aforesaid corresponding to the key depressed, from such key, thereby to permit the return of the motor-controlling device toward its normal position and the release of the type-bar corresponding to the key depressed in advance of the release of the key; all the parts being constructed, arranged and operating in such a manner that when a key is depressed to print, a succeeding key may be depressed to print while the key first depressed is still held down.

30. In a type-writing machine or other similar instrument, and in combination, (a) a plurality of type-bars; (b) a motor for actuating said type-bars; (c) keys corresponding to the type-bars actuated by the motor aforesaid, a different key for each different type-bar; (d) members equal in number to the type-bars aforesaid, said members being connected each with the corresponding type-bar and serving

to receive movement from the motor aforesaid, for the impelling of such type-bar; (e) key-impelled members corresponding to the keys aforesaid, each of said key-impelled members acting when its key is depressed to throw the type-bar-connected member aforesaid into operative relation with the motor aforesaid to receive movement therefrom; (f) a motor-controlling device, actuated by the keys through the key-impelled members aforesaid, and acting when a key is depressed to bring the motor aforesaid into action for the impelling of the type-bar corresponding to such key; and (g) a frame, acting when the key is depressed, upon the key-impelled member aforesaid corresponding to the key depressed, to disconnect said member from said key, thereby to permit the return of the motor-controlling device toward its normal position and the release of the type-bar corresponding to the key depressed, in advance of the release of the key.

31. In a type-writing machine or other similar instrument, and in combination, (a) a plurality of type-bars; (b) a motor for actuating said type-bars; (c) keys corresponding to the type-bars actuated by the motor aforesaid, a different key for each different type-bar; (d) members equal in number to the type-bars aforesaid, said members being connected each with the corresponding type-bar and serving to receive movement from the motor aforesaid, for the impelling of such type-bar; (e) key-impelled members corresponding to the keys aforesaid, each of said key-impelled members acting when its key is depressed to throw the type-bar-connected member aforesaid into operative relation with the motor aforesaid to receive movement therefrom; (f) a motor-controlling device, actuated by the keys through the key-impelled members aforesaid, and acting when a key is depressed to bring the motor aforesaid into action for the impelling of the type-bar corresponding to such key; and (g) a frame actuated by the motor aforesaid and acting upon the key-impelled member, corresponding to the key depressed, to disconnect said member from said key, thereby to permit the return of the motor-controlling device toward its normal position and the release of the type-bar, in advance of the release of the key depressed to control said type-bar; whereby another key may be depressed to print while the key first depressed is still held down.

32. In a type-writing machine or other similar instrument, and in combination, (a) a type-bar-impelling frame; (b) type-bars, impelled by said frame, each as required; (c) a motor for actuating the frame aforesaid, to impel the type-bars aforesaid; (d) keys corresponding to the type-bars actuated by the frame aforesaid, a different key for each different type-bar; (e) members equal in number to the type-bars aforesaid, said members being connected each with the corresponding type-bar and serving to receive movement

from the motor and frame aforesaid for the impelling of such type-bar; (f) key-impelled members corresponding to the keys aforesaid, each of said key-impelled members acting when its key is depressed to throw the type-bar-connected member aforesaid into operative relation with the frame aforesaid to receive movement therefrom; (g) motor-controlling means actuated by the keys aforesaid through the key-impelled members aforesaid, and acting when the keys are depressed, to bring the motor aforesaid into action for the impelling of the frame aforesaid and the type-bar connected therewith; and (h) means acting when a key is depressed to disconnect the key-impelled member corresponding to the key depressed, from such key; all the parts being constructed, arranged and operating in such a manner that when a key is depressed to print, a succeeding key may be depressed to print while the key first depressed is still held down.

33. In a type-writing machine or other similar instrument, and in combination, (a) a type-bar-impelling frame; (b) type-bars impelled by said frame, each as required; (c) a motor for actuating the frame aforesaid, to impel the type-bars aforesaid; (d) keys corresponding to the type-bars actuated by the frame aforesaid, a different key for each different type-bar; (e) members equal in number to the type-bars aforesaid, said members being connected each with the corresponding type-bar and serving to receive movement from the motor and frame aforesaid for the impelling of such type-bar; (f) key-impelled members corresponding to the keys aforesaid, each of said key-impelled members acting when its key is depressed to throw the type-bar-connected member aforesaid into operative relation with the frame aforesaid to receive movement therefrom; (g) motor-controlling means actuated by the keys aforesaid through the key-impelled members aforesaid, and acting when the keys are depressed, to bring the motor aforesaid into action for the impelling of the frame aforesaid and the type-bar connected therewith; and (h) means acting, when a key is depressed, to disconnect the key-impelled member corresponding to the key depressed, from such key; thereby to permit said member and the motor-controlling means actuated by the key depressed, through said member, to return toward their normal positions; the motor-controlling means aforesaid serving by such movement of return to affect the motor device aforesaid, so that the same leaves the frame aforesaid, with the type-bar impelled thereby, free to return toward their normal positions, in advance of the release of the key; whereby another key may be depressed to print while the key first depressed is still held down.

34. In a type-writing machine or other similar instrument, and in combination, (a) a type-bar-impelling frame; (b) type-bars, impelled by said frame, each as required; (c) a motor

for actuating the frame aforesaid, to impel the type-bars aforesaid; (d) keys corresponding to the type-bars actuated by the frame aforesaid, a different key for each different type-bar; (e) members equal in number to the type-bars aforesaid, said members being connected each with the corresponding type-bar and serving to receive movement from the motor and frame aforesaid for the impelling of such type-bar; (f) key-impelled members corresponding to the keys aforesaid, each of said key-impelled members acting when its key is depressed to throw the type-bar-connected member aforesaid into operative relation with the frame aforesaid to receive movement therefrom; (g) a motor-controlling device actuated by the keys through the key-impelled members aforesaid, and acting when a key is depressed, to bring the motor aforesaid into action for the impelling of the frame aforesaid, and the type-bar corresponding to the key depressed, the type-bar-impelling motor aforesaid acting to disconnect the key-impelled member aforesaid corresponding to the key depressed, from such key, thereby to permit the return of the motor-controlling device aforesaid toward its normal position and the release of the type-bar corresponding to the key depressed, in advance of the release of the key; all the parts being constructed, arranged and operating in such a manner that when a key is depressed to print, a succeeding key may be depressed to print while the key first depressed is still held down.

35. In a type-writing machine or other similar instrument, and in combination, (a) a type-bar-impelling frame; (b) type-bars, impelled by said frame, each as required; (c) a motor for actuating the frame aforesaid, to impel the type-bars aforesaid; (d) keys corresponding to the type-bars actuated by the frame aforesaid, a different key for each different type-bar; (e) members equal in number to the type-bars aforesaid, said members being connected each with the corresponding type-bar and serving to receive movement from the motor and frame aforesaid for the impelling of such type-bar; (f) key-impelled members corresponding to the keys aforesaid, each of said key-impelled members acting when its key is depressed to throw the type-bar-connected member aforesaid into operative relation with the frame aforesaid to receive movement therefrom; (g) a motor-controlling device actuated by the keys through the key-impelled members aforesaid, and acting when a key is depressed, to bring the motor aforesaid into action for the impelling of the frame aforesaid and the type-bar corresponding to the key depressed; and (h) a frame acting when a key is depressed, upon the key-impelled member aforesaid corresponding to the key depressed, to disconnect said member from said key, thereby to permit the return of the motor-controlling device toward its normal position and the release of the type-

bar corresponding to the key depressed, in advance of the release of the key; whereby another key may be depressed to print while the key first depressed is still held down. 70

36. In a type-writing machine or other similar instrument, and in combination, (a) a type-bar-impelling frame; (b) type-bars, impelled by said frame, each as required; (c) a motor for actuating the frame aforesaid, to impel the type-bars aforesaid; (d) keys corresponding to the type-bars actuated by the frame aforesaid, a different key for each different type-bar; (e) members equal in number to the type-bars aforesaid, said members being connected each with the corresponding type-bar and serving to receive movement from the motor and frame aforesaid for the impelling of such type-bar; (f) key-impelled members corresponding to the keys aforesaid, each of said key-impelled members acting when its key is depressed to throw the type-bar-connected member aforesaid into operative relation with the frame aforesaid to receive movement therefrom; (g) a motor-controlling device, actuated by the keys through the key-impelled members aforesaid, and acting when a key is depressed to bring the motor aforesaid into action for the impelling of the type-bar corresponding to such key; and (h) a releasing-frame actuated by the motor aforesaid, and acting when a key is depressed, upon the key-impelled member corresponding to the key depressed to disconnect said member from said key, thereby to permit the return of the motor-controlling device toward its normal position and the release of the type-bar, in advance of the release of the key depressed, to control said type-bar; whereby another key may be depressed to print while the key first depressed is still held down. 90

37. In a type-writing machine and in combination, (A) a plurality of type-bars, striking to a common printing-center; (B) keys, equal in number to said type-bars and each serving to control a different one of the type-bars aforesaid; (C) a motor; (D) a frame actuated thereby; (E) levers connected with the type-bars aforesaid; (F) members connected to said levers; (G) a connection between each key and the member connected with the lever aforesaid that is connected with the type-bar corresponding to such key; said connection acting when the key is depressed to communicate movement from said key to the movement-receiving member corresponding to said key, so as to bring said movement-receiving member into operative relation to the frame aforesaid, to receive movement therefrom, for the impelling of the type-bar; and (H) means acting to permit the type-bar to return to its normal position in advance of the release of the key; all the parts being constructed, arranged and operating in such a manner that when a key is depressed to print, a succeeding key may be depressed to print while the key first depressed is still held down. 100

38. In combination in a type-writing machine, (a) a type-bar; (b) a frame for giving movement to said type-bar; said frame being normally at rest; said type-bar being normally disconnected therefrom; (c) a lever corresponding to said type-bar; (d) a link connecting said lever with said type-bar; (e) a movement-receiving member pivoted to said lever; (f) a bell-crank connected with said movement-receiving member; (g) a key for actuating said bell-crank; and (h) a latch intermediate said key and said bell-crank.

39. In combination in a type-writing machine, (a) a type-bar; (b) a frame for giving movement to said type-bar; said frame being normally at rest; said type-bar being normally disconnected therefrom; (c) a lever corresponding to said type-bar; (d) a link connecting said lever with said type-bar; (e) a movement-receiving member pivoted to said lever; (f) a bell-crank connected with said movement-receiving member; (g) a key; (h) a latch intermediate said key and said bell-crank; (i) a motor for actuating the frame aforesaid; (k) a controlling device for said motor; said controlling device being operated by the key aforesaid through the latch aforesaid; and (l) means acting on said latch when the key is depressed, to free said latch in advance of the release of said key, thereby to permit the motor-controlling device aforesaid, the movement-receiving member aforesaid, and the motor-actuated frame aforesaid, to return toward their normal positions in advance of the release of said key, all the parts being constructed, arranged and operating in such a manner that a succeeding key may be depressed to print while the key first depressed is still held down.

40. In combination in a type-writing machine, (a) a type-bar; (b) a frame for giving movement to said type-bar; said frame being normally at rest; said type-bar being normally disconnected therefrom; (c) a lever corresponding to said type-bar; (d) a link connecting said lever with said type-bar; (e) a movement-receiving member pivoted to said lever; (f) a bell-crank connected with said movement-receiving member; (g) a key; (h) a latch intermediate said key and said bell-crank; (i) a motor for actuating the frame aforesaid; (k) a controlling device for said motor; said controlling device being operated by the key aforesaid through the latch aforesaid; and (l) a releasing-frame for freeing said latch; said releasing-frame acting when the key aforesaid is depressed, to free the latch aforesaid, thereby to permit the motor-controlling device aforesaid, the movement-receiving member aforesaid and the type-bar-impelling frame aforesaid, to return toward their normal positions in advance of the release of the key depressed, all the parts being constructed, arranged and operating in such a manner that a succeeding key may be depressed to print while the key first depressed is still held down.

41. In combination in a type-writing machine, (a) a type-bar; (b) a frame for giving movement to said type-bar; said frame being normally at rest; said type-bar being normally disconnected therefrom; (c) a lever corresponding to said type-bar; (d) a link connecting said lever with said type-bar; (e) a movement-receiving member pivoted to said lever; (f) a bell-crank connected with said movement-receiving member; (g) a key; (h) a latch pivoted to said bell-crank; (i) an arm connected with said bell-crank in such manner that it must move with said bell-crank when said bell-crank is moved in one direction by the key when said key is depressed, while said bell-crank is free to move in the reverse direction without moving said arm; (k) a link, connecting said arm with the movement-receiving member aforesaid; (l) a motor for actuating the frame aforesaid; (m) a controlling device for said motor, operated by the key aforesaid through the latch and bell-crank aforesaid; and (n) means for releasing the latch aforesaid.

42. In combination in a type-writing machine, (a) a type-bar; (b) a frame for giving movement to said type-bar; said frame being normally at rest; said type-bar being normally disconnected therefrom; (c) a lever corresponding to said type-bar; (d) a link connecting said lever with said type-bar; (e) a movement-receiving member pivoted to said lever; (f) a key; (g) a latch; (h) the bell-crank, 61; (i) the arm 60, operated by said bell-crank; (k) the link 59^a, connecting said arm 60 with the movement-receiving member aforesaid; (l) a motor, for actuating the frame aforesaid; (m) means for controlling said motor; said motor-controlling means being operated by the key aforesaid through the bell-crank aforesaid; and (n) means for freeing the latch aforesaid.

43. In a type-writing machine, and in combination therein with type-bars striking to a common printing-center, a releasing action including (a) a plurality of keys; (b) latches, corresponding to and actuated by said keys; (c) levers, corresponding to said keys and actuated by said keys through said latches; said levers being separate from the type-bars, but serving for the operating of said type-bars; (d) a hanger-bar, having grooves or slots formed therein to receive said levers; and (e) a rod set in said bar, and whereon said levers are mounted.

44. In combination in a type-writing machine, (a) a plurality of type-bars striking to a common printing-center; (b) a frame for giving movement to said type-bars, each as required; (c) levers corresponding to said type-bars, a lever for each type-bar that is operated by the frame aforesaid; (d) links connecting said type-bars with said levers; (e) movement-receiving members pivoted to said type-bar corresponding levers, a movement-receiving member to each type-bar corresponding lever; (f) keys, corresponding to

said movement-receiving members, a key for each movement-receiving member; (g) connections intermediate said keys and said movement-receiving members wherethrough 5 each key, when depressed, gives movement to the corresponding movement-receiving member to bring said member into operative relation with the frame aforesaid; and (h) means acting, when a key is depressed, to permit the movement-receiving member corresponding to said key to return toward its normal position in advance of the release of said key, thereby to permit the frame aforesaid to 10 actuate another movement-receiving member 15 while the key first depressed is still held down, without again actuating the movement-receiving member corresponding to the key depressed until said key has been released and again depressed.

20 45. In combination in a type-writing machine, (a) a plurality of type-bars striking to a common printing-center; (b) a frame for giving movement to said type-bars, each as required; (c) levers corresponding to said 25 type-bars, a lever for each type-bar that is operated by the frame aforesaid; (d) links connecting said type-bars with said levers; (e) movement-receiving members pivoted to said type-bar corresponding levers, a movement-receiving member to each type-bar corresponding lever; (f) keys, corresponding 30 to said movement-receiving members; (g) latches intermediate said keys and the movement-receiving members aforesaid; (h) a motor 35 for actuating the frame aforesaid; (i) a controlling device for said motor, common to a plurality of the keys aforesaid and actuated by said keys through the latches aforesaid; and (k) means acting when a key is depressed 40 and the motor aforesaid thereby brought into action, to free the latch corresponding to said key, thereby to permit the movement-receiving member corresponding to said key to return toward its normal position in advance of 45 the release of said key, and to permit also the motor-controlling device aforesaid to return toward its normal position in advance of the release of said key; said motor-controlling device operating by such its return movement to affect the motor device aforesaid in such manner that the type-bar-actuating frame aforesaid returns toward its normal position in advance of the release of the key depressed; whereby another key may be depressed to print while the key first depressed 50 is still held down.

46. In combination in a type-writing machine, (a) a plurality of type-bars striking to a common printing-center; (b) a frame for giving movement to said type-bars, each as required; (c) levers corresponding to said type-bars, a lever for each type-bar that is operated by the frame aforesaid; (d) links connecting said type-bars with said levers; (e) movement- 60 receiving members pivoted to said type-bar corresponding levers, a movement-receiving member to each type-bar corresponding lever;

(f) keys, corresponding to said movement-receiving members; (g) latches intermediate said keys and the movement-receiving members aforesaid; (h) a motor for actuating the frame aforesaid; (i) a controlling device for said motor, common to a plurality of the keys aforesaid and actuated by said keys through the latches aforesaid; and (k) a releasing-frame common to a plurality of the latches aforesaid; said releasing-frame being controlled by the keys corresponding to said latches and serving when any of said keys has been depressed, to free the latch corresponding to said key depressed, thereby to permit the movement-receiving member corresponding to said key to return toward its normal position in advance of the release of said key, and to permit also the motor-controlling device aforesaid to return toward its normal position in advance of the release of said key; said motor-controlling device operating by such its return movement to affect the motor device aforesaid in such manner that the type-bar-actuating frame aforesaid returns toward its normal position in advance of the release of the key depressed; whereby another key may be depressed to print while the key first depressed is still held down.

47. In combination in a type-writing machine, (a) a plurality of type-bars striking to a common printing-center; (b) a frame for giving movement to said type-bars, each as required; (c) levers corresponding to said type-bars, a lever for each type-bar that is operated by the frame aforesaid; (d) links connecting said type-bars with said levers; (e) movement-receiving members pivoted to said type-bar corresponding levers, a movement-receiving member to each type-bar corresponding lever; (f) keys, corresponding to said movement-receiving members; (g) latches intermediate said keys and the movement-receiving members aforesaid; (h) a motor for actuating the frame aforesaid; (i) a controlling device for said motor, common to a plurality of the keys aforesaid and actuated by said keys through the latches aforesaid; and (k) a releasing device common to a plurality of the latches aforesaid; said releasing device being operated by the motor aforesaid and serving when a key controlling one of the latches to which it is common is depressed, to free said latch, thereby to permit the movement-receiving member corresponding to said key to return toward its normal position in advance of the release of said key, and to permit also the motor-controlling device aforesaid to return toward its normal position in advance of the release of said key; said motor-controlling device operating by such its return movement to affect the motor device aforesaid in such manner that the type-bar-actuating frame aforesaid returns toward its normal position in advance of the release of the key depressed; whereby another key may be depressed to print while the key first depressed is still held down.

48. In combination in a type-writing machine, (a) an alphabet of type-bars striking to a common printing-center; (b) keys corresponding to said type-bars, a key for each 5 type-bar; (c) latches corresponding to and operated by said keys; (d) means operated by said latches for actuating said type-bars, each as required; and (e) means controlled by the keys aforesaid acting when a key is 10 depressed, and is at rest in its depressed position, to free the latch corresponding to said key in advance of the release of said key, whereby another key may be depressed to print while the key first depressed is still held down.

49. In combination in a type-writing machine, (a) an alphabet of type-bars striking to a common printing-center; (b) keys corresponding to said type-bars, a key for each 20 type-bar; (c) latches corresponding to and operated by said keys; (d) means operated by said latches for actuating said type-bars, each as required; and (e) a device common 25 to a plurality of said latches and acting when any key controlling one of said latches to which said device is common is depressed, upon the latch corresponding to such key depressed, to free said latch in advance of the release of said key, whereby another key may 30 be depressed while the key first depressed is still held down.

50. In combination in a type-writing machine, (a) an alphabet of type-bars striking to a common printing-center; (b) keys corresponding to said type-bars, a key for each 35 type-bar; (c) latches corresponding to and operated by said keys; (d) means operated by said latches for actuating said type-bars, each as required; and (e) a key-controlled 40 releasing-frame common to a plurality of said latches, and acting when any key controlling one of the latches to which it is common is depressed, to free said latch in advance of the release of said key, whereby another key 45 may be depressed, while the key first depressed is still held down.

51. In combination in a type-writing machine, (a) an alphabet of type-bars striking to a common printing-center; (b) keys corresponding to said type-bars, a key for each 50 type-bar; (c) latches corresponding to and operated by said keys; (d) means operated by said latches for actuating said type-bars, each as required; and (e) a single releasing-frame 55 common to all said latches and controlled by said keys, and acting when any of said keys is depressed, to free the latch operated by said key in advance of the release of said key; whereby another key may be depressed 60 while the key first depressed is still held down.

52. In combination in a type-writing machine, (a) an alphabet of type-bars striking to a common printing center; (b) keys corresponding to said type-bars, a key for each 65 type-bar; (c) latches corresponding to said keys, a latch for each key; said latches be-

ing operated by the keys to which they respectively correspond; (d) motor mechanism for actuating the type-bars aforesaid, each as required; said motor mechanism being controlled by the keys aforesaid through the latches aforesaid; and (e) means controlled by the keys aforesaid acting when a key is depressed, to free the latch corresponding to 70 said key in advance of the release of said key; whereby another key may be depressed to print while the key first depressed is still held down.

53. In combination in a type-writing machine, (a) an alphabet of type-bars striking to a common printing-center; (b) keys corresponding to said keys, a latch for each key; said latches being 80 operated by the keys to which they respectively correspond; (d) motor mechanism for actuating the type-bars aforesaid, each as required; said motor mechanism being controlled by the keys aforesaid through the 85 latches aforesaid; and (e) a device common to a plurality of the latches aforesaid, acting when any of the keys controlling said latches is depressed, to free the latch corresponding to 90 said key, whereby another key may be depressed to print while the key first depressed is still held down.

54. In combination in a type-writing machine, (a) an alphabet of type-bars striking to a common printing-center; (b) keys corresponding to said type-bars, a key for each 100 type-bar; (c) latches corresponding to said keys, a latch for each key; said latches being operated by the keys to which they respectively correspond; (d) motor mechanism for 105 actuating the type-bars aforesaid, each as required; said motor mechanism being controlled by the keys aforesaid through the latches aforesaid; and (e) a key-controlled releasing-frame, common to a plurality of the 110 latches aforesaid and acting when any of the keys controlling one of the latches to which said releasing-frame is common is depressed, to free the latch controlled by said key depressed, whereby another key may be depressed 115 to print while the key first depressed is still held down.

55. In combination in a type-writing machine, (a) an alphabet of type-bars striking to a common printing-center; (b) keys corresponding to said type-bars, a key for each 120 type-bar; (c) latches corresponding to said keys, a latch for each key; said latches being operated by the keys to which they respectively correspond; (d) motor mechanism for 125 actuating the type-bars aforesaid, each as required; said motor mechanism being controlled by the keys aforesaid through the latches aforesaid; and (e) a key-controlled motor-operated device common to a plurality 130 of the latches aforesaid and acting when any of the keys controlling one of the latches to which said device is common is depressed, to free the latch controlled by said key de-

pressed, whereby another key may be depressed to print while the key first depressed is still held down.

56. In combination in a type-writing machine, (a) a type-bar; (b) paper-feeding mechanism, whereby the paper is advanced step by step as the printing progresses; (c) a single motor device, serving to actuate both the type-bar aforesaid and the paper-feeding mechanism aforesaid; (d) a key, controlling said motor device; (e) releasing means, acting when said key is depressed to release both the type-bar aforesaid and the paper-feeding mechanism aforesaid in advance of the release of the key depressed, all the parts being constructed, arranged and operated in such a manner that when a key is depressed to print the parts are released, so that another key can be depressed to print without waiting to release the key first depressed.

57. In combination in a type-writing machine, (a) a type-bar; (b) paper-feeding mechanism, whereby the paper is advanced step by step as the printing progresses; (c) a single motor device, serving to actuate both the type-bar aforesaid and the paper-feeding mechanism aforesaid; (d) a controlling device for said motor; (e) a key; (f) a latch intermediate said key and said motor-controlling device, wherethrough said key when depressed operates said motor-controlling device; (g) means acting when said key has been depressed to free said latch, thereby to permit the motor-controlling device aforesaid to return toward its normal position in advance of the release of said key; whereby another key may be depressed to print while the key first depressed is still held down.

58. In combination in a type-writing machine, (a) a type-bar; (b) paper-feeding mechanism, whereby the paper is advanced step by step as the printing progresses; (c) a single motor device, serving to actuate both the type-bar aforesaid and the paper-feeding mechanism aforesaid; (d) a controlling device for said motor; (e) a key; (f) a latch intermediate said key and said motor-controlling device, wherethrough said key when depressed operates said motor-controlling device; and (g) means actuated by the motor aforesaid serving, when the key aforesaid is depressed, to free the latch aforesaid, thereby to permit the motor-controlling device aforesaid to return toward its normal position in advance of the release of said key; whereby another key may be depressed to print while the key first depressed is still held down.

59. In combination in a type-writing machine, (a) a type-bar; (b) paper-feeding mechanism, whereby the paper is advanced step by step as the printing progresses; (c) a single electromagnet serving to actuate both the type-bar aforesaid and the paper-feeding mechanism aforesaid; (d) a key controlling said magnet; and (e) means acting when said key is depressed to release both the type-bar aforesaid and the paper-feeding mechanism

aforesaid in advance of the release of said key, whereby another key may be depressed to print while the key first depressed is still held down.

60. In combination in a type-writing machine, (a) a type-bar; (b) paper-feeding mechanism, whereby the paper is advanced step by step as the printing progresses; (c) a single electromagnet serving to actuate both the type-bar aforesaid and the paper-feeding mechanism aforesaid; (d) a circuit-controlling device for said electromagnet; (e) a key; (f) a latch intermediate said key and said circuit-controlling device wherethrough said key, when depressed, operates said circuit-controlling device to bring the electromagnet aforesaid into action to operate the type-bar aforesaid and the paper-feeding mechanism aforesaid; and (g) means acting, when said key has been depressed, to free said latch, thereby to permit the circuit-controlling device aforesaid to return toward its normal position in advance of the release of said key, whereby another key may be depressed to print while the key first depressed is still held down.

61. In combination in a type-writing machine, (a) a plurality of type-bars striking to a common printing-center; (b) a paper-carriage; (c) spacing mechanism controlling the letter-space movements of said paper-carriage; (d) a motor device for actuating both the type-bars aforesaid and the spacing mechanism aforesaid; said type-bars being normally disconnected from said motor device; (e) keys; (f) means controlled by said keys for connecting the different type-bars aforesaid each as required, with the motor device aforesaid, and for bringing said motor device into action to operate the type-bar thus connected with it, and the spacing mechanism aforesaid; and (g) releasing means whereby when a key is depressed and the type-bar corresponding to said key actuated and the spacing mechanism aforesaid actuated by the motor device aforesaid, said type-bars and spacing mechanism are left free to return toward their normal positions in advance of the release of said key, all the parts being constructed, arranged and operating in such a manner that a succeeding key may be depressed to print while the key first depressed is still held down.

62. In combination in a type-writing machine, (a) a plurality of type-bars striking to a common printing-center; (b) a paper-carriage; (c) spacing mechanism controlling the letter-space movements of said paper-carriage; (d) a vibratory frame for giving movement to the type-bars aforesaid each as required; said type-bars being normally disconnected from said frame, and said frame being normally at rest; (e) a motor for actuating said vibratory frame; said motor serving also to actuate the spacing mechanism aforesaid; (f) keys; (g) latches operated by said keys; (h) means operated by said keys

through said latches for connecting the type-bars aforesaid, each as required, with the frame aforesaid, and for bringing the motor aforesaid into action to operate the frame aforesaid and the spacing mechanism aforesaid; and (i) means acting when a key is depressed, upon the latch operated by said key, to free said latch; all the parts being constructed, arranged and operating in such a manner that a succeeding key may be depressed to print while the key first depressed is still held down.

63. In combination in a type-writing machine, (a) a plurality of type-bars striking to a common printing-center; (b) a paper-carriage; (c) spacing mechanism controlling the letter-space movements of said paper-carriage; (d) a vibratory frame for giving movement to the type-bars aforesaid, each as required; said type-bars being normally disconnected from said frame, and said frame being normally at rest; (e) a motor for actuating said vibratory frame; said motor serving also to actuate the spacing mechanism aforesaid; (f) keys; (g) latches operated by said keys; (h) means operated by said keys through said latches for connecting the type-bars aforesaid, each as required, with the frame aforesaid, and for bringing the motor aforesaid into action to operate the frame aforesaid and the spacing mechanism aforesaid; and (i) a releasing-frame common to a plurality of the latches aforesaid; said releasing-frame being operated by the motor aforesaid and acting when a key is depressed, upon the latch operated by said key, to free said latch; whereby another key may be depressed while the key first depressed is still held down.

64. In a type-writing machine or other similar instrument, the combination with type-bars having each three characters and a platen, of a shifting mechanism therefor, including (a) two members normally spring-pressed against a central stop; (b) a pin connected with the platen and lying between said spring-pressed members; and (c) stops serving to limit the movement of said spring-pressed members from their normal position.

65. In a type-writing machine or other similar instrument, and in combination, (a) a shifting platen; (b) a frame wherein said platen is mounted to rotate and to move longitudinally as the letters are printed; said frame being mounted also to move transversely to the length of the platen to shift the printing-points; (d) one or more shift-keys; (e) a member connected with said key or keys and acting upon the platen-carrying frame to shift the platen transversely to its length; (f) a pin in said member; (g) centralizing members, lying on each side of said pin, and normally spring-pressed against a fixed stop, thereby to hold the platen normally in its central position; and (h) stops to limit the movement of said centralizing members when moved from their normal positions.

66. In a type-writing machine or other similar instrument, the combination with the paper-carrying platen and a frame moving therewith, of (a) a member 130, furnished with a projection 136; (b) the stop 135; (c) the centralizing members 132, 132, normally bearing against said stop 135, and lying on opposite sides of the projection 136 aforesaid; and (d) the stops 137, 137 whereby the play of the members 132, 132 is limited.

67. In a type-writing machine or other similar instrument, the combination with the paper-carrying platen and a frame moving therewith, of (a) a member 130, furnished with a projection 136; (b) the stop 135; (c) the centralizing members 132, 132, normally bearing against said stop 135, and lying on opposite sides of the projection 136 aforesaid; (d) the stops 137, 137 whereby the play of the members 132, 132 is limited; and (e) two space-keys, acting to move the member 130 in opposite directions from its central position.

68. In a type-writing machine or other similar instrument, the combination with the paper-carrying platen and a frame moving therewith, of (a) a member 130, furnished with a projection 136; (b) the stop 135; (c) the centralizing members 132, 132, normally bearing against said stop 135, and lying on opposite sides of the projection 136 aforesaid; (d) the stops 137, 137 whereby the play of the members 132, 132 is limited; (e) two shift-keys, acting to move the member 130 in opposite directions from its normal position; and (f) a rock-shaft having an arm 129 connected to the member 130 and having other arms connected with the shift-keys aforesaid.

69. In combination, in a keyboard printing instrumentality, (a) an alphabet of keys; (b) latches corresponding to said keys, a latch for each key; (c) letter-controlling mechanism operated by said keys through said latches; and (d) releasing mechanism acting when a key is depressed and is at rest in its depressed position, upon the latch corresponding to said key, to free said latch, thereby to permit the parts operated by said key through said latch to return toward their normal positions in advance of the release of said key; whereby another key may be depressed to print while the key first depressed is still held down.

70. In combination, in a keyboard printing instrumentality, (a) an alphabet of keys; (b) latches corresponding to said keys, a latch for each key; (c) letter-controlling mechanism operated by said keys through said latches; and (d) a releasing device, common to a plurality of the latches aforesaid and acting when a key controlling any of said latches is depressed, to free the latch operated by the key depressed, thereby to permit the parts operated by said key through said latch to return toward their normal positions in advance of the release of said key; whereby another key may be depressed to print while the key first depressed is still held down.

71. In combination, in a keyboard printing

instrumentality, (a) an alphabet of keys; (b) latches corresponding to said keys, a latch for each key; (c) letter-controlling mechanism operated by said keys through said latches; 5 and (d) a key-controlled releasing-frame common to a plurality of the latches aforesaid and acting when a key controlling any of said latches is depressed, to free the latch operated by the key depressed, thereby to permit the 10 parts operated by said key through said latch to return toward their normal positions in advance of the release of said key; whereby another key may be depressed while the key first depressed is still held down.

15 72. In combination, in a keyboard printing instrumentality, (a) an alphabet of keys; (b) latches corresponding to said keys, a latch for each key; (c) letter-controlling mechanism operated by said keys through said latches; 20 and (d) motor mechanism controlled by the keys aforesaid, said motor mechanism being normally at rest, but acting when a key is depressed, to free the latch corresponding to said key, thereby to permit the parts operated 25 by said key through said latch to return toward their normal positions in advance of the release of said key; whereby another key may be depressed to print while the key first depressed is still held down.

30 73. In combination, in a keyboard printing instrumentality, (A) an alphabet of letter-controlling elements; (B) keys equal in number to the letter-controlling elements before mentioned; each of said keys being connected 35 to control the corresponding letter-controlling element; the keys being arranged in two banks and shaped piano fashion, and consisting of two groups, one for the right hand and the other for the left hand, arranged in juxtaposition, each group including (a) four keys in each of the two banks aforesaid, normally disposed to be conveniently operated each by the appropriate one of the four fingers, with the hand in its normal position; (b) a plurality of keys arranged to be operated by the thumb; and (c) a plurality of keys in a bank back of the thumb-keys aforesaid and disposed in such a position as to be conveniently operated by the thumb or forefinger.

40 74. In combination in a keyboard printing instrumentality, (a) an alphabet of letter-controlling elements; (b) a motor device serving to actuate a plurality of said letter-controlling elements, each as required; (c) keys 45 equal in number to said letter-controlling elements; said keys each acting when depressed to connect the corresponding letter-controlling element with the motor device aforesaid to receive movement therefrom; (d) a motor-controlling device, operated by a plurality of the keys aforesaid and acting when one of said keys is depressed to bring the motor device aforesaid into action for the impelling of the letter-controlling element connected with 50 it by the key depressed; and (e) means acting to release said motor-controlling device, in advance of the release of the key.

75. In combination in a keyboard printing instrumentality, (a) an alphabet of letter-controlling elements; (b) a motor device serving to actuate a plurality of said letter-controlling elements, each as required; (c) keys equal in number to said letter-controlling elements; said keys each acting when depressed to connect the corresponding letter-controlling element with the motor device aforesaid to receive movement therefrom; (d) a motor-controlling device, operated by a plurality of the keys aforesaid and acting when one of said keys is depressed to bring the motor device aforesaid into action for the impelling of the letter-controlling element connected with it by the key depressed; and (e) means actuated by the motor device aforesaid and acting to release the motor-controlling device aforesaid in advance of the release of the key controlling it.

76. In combination in a keyboard printing instrumentality, (a) an alphabet of letter-controlling elements, (b) an electromagnet, acting to impel a plurality of said letter-controlling elements; (c) keys equal in number to said letter-controlling elements, and each acting when depressed, to connect the corresponding letter-controlling element with the electromagnet aforesaid, to receive movement therefrom; (d) a circuit-closing device, operated by a plurality of the keys aforesaid and acting when one of said keys is depressed, to close the circuit of the electromagnet aforesaid; and (e) means acting to release said circuit-closing device in advance of the release of the key controlling it, whereby another key may be depressed while the key first depressed is still held down.

77. In combination in a keyboard printing instrumentality, (a) an alphabet of letter-controlling elements; (b) an electromagnet, acting to impel a plurality of said letter-controlling elements; (c) keys equal in number to said letter-controlling elements, and each acting when depressed, to connect the corresponding letter-controlling element with the electromagnet aforesaid, to receive movement therefrom; (d) a circuit-closing device, operated by a plurality of the keys aforesaid, and acting when one of said keys is depressed, to close the circuit of the electromagnet aforesaid; and (e) means operated by the electromagnet aforesaid; acting to release the circuit-closing device aforesaid in advance of the release of the key controlling it, whereby another key may be depressed while the key first depressed is still held down.

78. In combination in a keyboard printing instrumentality, (A) an alphabet of letter-controlling elements; (B) keys equal in number to the letter-controlling elements before mentioned, said keys being each connected to control the corresponding letter-controlling element; the keys of the instrument being arranged in two banks, and shaped piano fashion, and consisting of two groups, one for the right hand and the other for the left hand,

arranged in juxtaposition, each group including (a) four keys in each of the two banks aforesaid, normally disposed to be conveniently operated each by the appropriate one 5 of the four fingers, with the hand in its normal position; (b) a plurality of keys, arranged to be operated by the thumb; (c) a plurality of keys in a bank back of the thumb-keys aforesaid and disposed in such a position as to be conveniently operated by the thumb or forefinger; (C) a motor for actuating a plurality of the letter-controlling elements aforesaid; and (D) means controlled by the keys afore-

said and acting to connect the letter-controlling elements for which said motor serves 15 with said motor, to receive movement therefrom, each as required.

In testimony whereof I have hereunto set my hand, at Washington, in the District of Columbia, this 23d day of December, A. D. 20 1898, in the presence of the subscribing witnesses whose names are hereto annexed.

THADDEUS CAHILL.
